UNITED STATES PATENT OFFICE.

JOSEPH F. JOY, OF PITTSBURGH, PENNSYLVANIA.

MEANS FOR RAILWAY-TRACK EXTENSION.

1,392,648.

Specification of Letters Patent. Patented Oct. 4, 1921.

Application filed July 23, 1920. Serial No. 398,376.

To all whom it may concern:

Be it known that I, JOSEPH F. JOY, a citizen of the United States of America, residing at Pittsburgh, in the county of Allegheny and State of Pennsylvania, have invented certain new and useful Improvements in Means for Railway-Track Extension, of which the following is a specification.

10 This invention relates to certain new and useful improvements in means for railway track extension and is particularly serviceable in connection with the extension of the light-weight trackage found in coal mines 15 and especially for extending the tracks in mine rooms for any desired distance less than the length of full length rail sections.

In the mining of coal under the room-and-pillar system, the face of the vein is usually 20 undercut for a depth substantially equal to the width of the working place, after which the material is blasted and loaded out by mechanical loaders or the like for the depth of such cut. The preferred types of loading 25 machines are constructed to run upon rails so that the same may be readily brought up to within a short distance of the working face, and in order to accomplish this the rails must be kept extended close to the 30 working face as the loading out of the coal proceeds. As the length of track extension required after the loading out of each cut is considerably less than the length of full length rail sections, special length rails must 35 be employed for extending the track at considerable expense under present methods. It is the primary object of the present invention to employ full length rail sections of the standard type manufactured for thus 40 extending the tracks any desired part of the length of the rail sections by splicing in a novel manner.

It is a further object of the present invention to provide means including a novel rail 45 clamp to enable full length rail sections to be thus spliced.

A still further object of the invention is to construct a tie clamp so as to enable the same to be cheaply and easily manufactured 50 as well as readily placed in use for the above and other purposes.

Other objects will become apparent as the nature of the invention is better understood, and the same consists in the novel form, 55 combination and arrangement of parts here-

inafter more fully described, shown in the accompanying drawing and claimed.

In the drawings, wherein like reference characters indicate similar parts throughout the several views,

Figure 1 is a fragmentary view partly in elevation and partly in transverse vertical section showing my improved clamp associated with a pair of rail sections, one of which is shown by dotted lines,

Fig. 2 is substantially a top plan view of the device shown in Fig. 1,

Fig. 3 is a view partly in vertical section and partly in elevation of the rail clamp shown in Figs. 1 and 2, the clamp being 70 shown on an enlarged scale,

Fig. 4 is a top plan view of the tie clamp with the nut and set screw removed,

Fig. 5 is a transverse sectional view taken upon line V—V of Fig. 4,

Fig. 6 is a somewhat diagrammatic plan view illustrating the manner in which the rails are spliced in accordance with the present invention for extending the track a certain distance, and

Fig. 7 is a view similar to Fig. 6 after the rails have been further extended subsequent to the loading out of the cut illustrated in Fig. 6.

Referring more in detail to the several views, the present invention embodies a tie clamp including a body member 5 of substantially Greek cross form in plan and including aligned oppositely extending jaws 6 having upwardly inclined lower faces 7 as 90 more clearly shown in Figs. 1 and 6. The body of the clamp between the jaws 6 is provided with opposite lateral extensions 8 from which depend hook-shaped flanges 9 for engagement with the side and under- 95 faces of the bar tie 10 so that the clamp may be slid to any position on said tie as desired. The body 5 is centrally apertured as at 10 and is provided with a countersunk squared socket 11 coincident with and beneath the 100 aperture 10 for snug reception of a nut 12. The nut 12 may be merely fitted in the socket 11 or the same may be permanently secured therein by welding or the like and it will be seen that the nut is effectively prevented from turning relative to the body 5 by reason of the angular form of the nut and the socket. A set screw 13 is passed through the aperture 10 and threaded

105 through the nut 12 so that its inner end is 110

positioned to bear upon the upper surface of the tie 10, and it will thus be obvious that the clamp, or a number of the same, may be slid to the desired position or positions upon the tie, after which the set screw 13 of each clamp may be threaded inwardly for drawing the lower ends of the hooks 9 tightly against the under surface of the tie and rigidly fastening the clamp or clamps 5 in position against displacement, the under surfaces 7 of each clamp being at such times in engagement with the upper surface of the adjacent base flange of the rail A. When the clamp is used between two rails 15 as indicated in Fig. 1, the under surfaces 7 of both jaws engage a rail base flange so that the same is particularly serviceable in splicing rails for track extension as will presently become apparent.

Referring to Figs. 6 and 7, 14 indicates a mine room whose working face —a— is undercut as at —b— in the usual manner. In Fig. 6, the rails A have been extended into the room in end to end relation for full 25 length to the points —c— so that the distance between said points —c— and the working face is not sufficient to admit the extension of the tracks for the distance of the full length of a rail section. As the 30 tracks must be extended substantially to the working face or to the points —d—, it is necessary to provide some feasible means for employing full length rail sections for this purpose or special length sections must 35 be employed at increased expense. In order to make use of full length rails for this extension of the tracks, I place ordinary switch points 15 against the ends of the rails A and then place the rail sections A' 40 alongside of the switch points and the rails A so that said rail sections A' extend to the points —d—. The ties 10 are then placed under the rails at the required points and the forward ends of the rail sections A' are 45 clamped in their desired distance apart by the use of the clamps 5 hereinbefore described and shown in Figs. 1 to 5 inclusive.

As the trackage employed in mines is of 50 very little weight and somewhat flexible, the rail sections A' are then sprung outwardly for a slight distance where they overlap the switch points 15 and the rails A, after which the switch points, the rail sections A' and the rails A are rigidly clamped 55 together in the relation shown in Fig. 6 by proper use of the clamps 5, one clamp 5 being employed for engaging the base flanges of both the rail sections A' and the rails A at the points —e— so as to insure 60 retention of the rail sections A' in their sprung conditions.

When the coal has been mined or loaded 65 out for the depth of the undercut —b— so as to provide a new working face —a'— as shown in Fig. 7, the tracks must be further

extended. When the rail points are staggered, it often happens that one full length rail section A' may be inserted while a splicing in overlapped relation is necessary with respect to the other rail section as 70 shown in Fig. 7.

When this is the case, the left hand rail section A' is placed against the end of the left hand rail A while the right hand rail section A' is merely moved forwardly and 75 again spliced in the manner shown in Fig. 6 by springing said section A' and using a switch point 15, the rails being still rigidly maintained in their proper relation by use of the same clamps 5 upon the ties 10. As 80 the springing of the rail sections A' does not produce a permanent bend in the latter, the same will immediately return to their substantially straight form when released. 85

In the use of the clamps of the present invention, the desired number of clamps are first slid onto each tie 10, and the latter with the clamps are then placed under the rails in any suitable manner, such as by 90 jacking the rails up sufficiently for this purpose. The clamps are then placed at their proper relative positions and engage with the base flanges of the rails, after which the set screws 13 are manipulated for fastening the rails in their proper relation. 95

From the foregoing description, it will be seen that I have provided an extremely practical means for track extension particularly serviceable in the rooms of coal mines 100 for enabling the use of full length rail sections even though the length of extension from time to time is considerable less than the length of full length rail sections.

It is believed that the construction and 105 operation as well as the advantages of the present invention will be readily understood and appreciated by those skilled in the art.

Minor changes may be made without departing from the spirit and scope of the invention as claimed. 110

What is claimed as new is:

1. In a means for railway track extension, a rail tie clamp comprising a body of substantially Greek cross form in plan and including alined oppositely directed jaws adapted for engagement upon the base flanges of adjacent rails, means for slidably connecting the body to a bar tie, said body having an angular socket therein, a nut fitted in said socket, and a set screw threaded through said nut for engagement with the upper surface of a tie. 115

2. In a means for railway track extension, a rail tie clamp comprising a body of substantially Greek cross form in plan and including alined oppositely directed jaws adapted for engagement upon the base flanges of adjacent rails, means for slidably connecting the body to a bar tie, said last 120 125 130

- named means comprising alined oppositely directed extensions between said jaws provided with depending opposed hook-shaped flanges, said body having a central aperture 5 and being provided with an angular socket coincident with said aperture, an angular nut fitted in said socket, and a set screw threaded through said nut adapted for engagement with the upper surface of a tie to 10 retain the clamp against movement relative to said tie.
3. In a means for railway track extension, a rail tie clamp comprising a body having alined oppositely directed jaws adapted for 15 engagement upon the base flanges of adjacent rails, means for slidably connecting the body to a bar tie, said body having an angular socket therein, a nut fitted in said socket, and a set screw threaded through 20 said nut for engagement with a surface of the tie.
4. In a means for railway track extension, a rail tie clamp comprising a body having alined oppositely directed jaws adapted for 25 engagement upon the base flanges of adjacent rails, means for slidably connecting the body to a bar tie, said last named means including depending opposed hook-shaped flanges rigid with the body, said clamp having 30 an aperture and being provided with an angular socket coincident with said aperture, an angular nut fitted in said socket, and a set screw threaded through said nut adapted for engaging with a surface of the 35 tie to retain the clamp against movement relative to the latter.
5. A rail tie clamp comprising a body having a jaw adapted for engagement upon the base flange of a rail and provided with 40 means for slidably connecting the same to a bar tie, said clamp having an angular
- socket therein, a nut fitted in said socket, and a set screw threaded through said nut for engagement with a surface of the tie for holding the clamp against sliding movement 45 on the latter.
6. A rail tie clamp comprising a body having a jaw adapted for engagement upon the base flange of a rail and provided with means for slidably connecting the same to 50 a bar tie, said clamp having an angular socket therein, a nut fitted in said socket, and a set screw threaded through said nut for engagement with a surface of the tie for holding the clamp against sliding move- 55 ment on the latter, said means for slidably connecting the clamp to the tie including depending opposed hook-shaped flanges on the body.
7. A rail tie clamp comprising a body 60 having a jaw adapted for engagement upon the base flange of a rail, means for slidably connecting the body to a bar tie, said last named means comprising depending opposed hook shaped flanges, said body having 65 a central aperture and being provided with an angular socket coincident with said aperture, an angular nut fitted in said socket, and a set screw threaded through said nut adapted for engagement with the upper sur- 70 face of a tie to retain the clamp against movement relative to said tie.
8. A rail tie clamp comprising a body having a jaw adapted for engagement upon the base flange of a rail, means for slidably 75 connecting the body to a bar tie, said body having an angular socket therein, a nut fitted in said socket, and a set screw threaded through said nut adapted for engagement with the upper surface of a tie. 80

In testimony whereof I affix my signature.
JOSEPH F. JOY.
